UNITED STATES PATENT OFFICE.

JOHN B. POWELL, OF PHILADELPHIA, PENNSYLVANIA, ASSIGNOR TO
WILLIAM A. DROWN, OF SAME PLACE.

UMBRELLA CATCH AND RUNNER.

SPECIFICATION forming part of Letters Patent No. 288,486, dated November 13, 1883.

Application filed June 7, 1883. (No model.)

To all whom it may concern:

Be it known that I, JOHN B. POWELL, a citizen of the United States, residing at Philadelphia, in the county of Philadelphia and State of Pennsylvania, have invented certain new and useful Improvements in Umbrella Catches and Runners; and I do hereby declare the following to be a full, clear, and exact description of the invention, reference being had to the accompanying drawings, which form part of this specification, in which—

Figure 1 is a side elevation of spring-catch on stick. Fig. 2 is a side elevation of runner. Fig. 3 is a vertical elevation of catch and runner on stick, and Fig. 4 is a side view of same. Fig. 5 is a transverse section of runner and stick. Fig. 6 is a perspective of catch.

My invention has for its object to provide an improved catch for umbrella-runners which will dispense with cutting the stick for its attachment thereto, and which for its operation will require the same manipulation as an ordinary umbrella-catch.

My improvements consist in the peculiar construction of the spring-catch, hereinafter described, and of the sleeve or runner used in conjunction therewith, as well as in the combination of said catch and runner with each other and with the umbrella-stick.

Referring to the accompanying drawings, A indicates an umbrella-stick, and B a runner designed and adapted to slide thereon for the purpose of opening and closing the umbrella. Said runner consists of a tubular sleeve, b, and a notch, C, to which latter the ends of the stretchers are to be secured in the usual or any suitable manner.

The sleeve b has on one side a longitudinal groove or channel, b', forming a passage-way for the catch hereinafter described, and the notch C has an opening, c, registering with said groove and forming an entrance or opening thereto. Flaring projections b² b², consisting of parts of the sleeve b, projecting beyond the notch C, form guides to the opening c in the latter.

D represents a metal collar or ring secured to the umbrella-stick A, near the upper end thereof, and in such position that the catch of which it forms the base will duly engage, as

hereinafter described, with the runner when the umbrella is opened. Said ring or collar is fastened to the stick by pins d d, driven into the latter, or in any suitable and equivalent manner.

Secured to the collar D, and projecting downwardly therefrom, is a catch, E, consisting of a steel spring, e, with head e', which latter may be integral with the spring or of different metal, and secured to said spring. The lower end of the head e' is beveled or inclined, so as to readily enter the opening c in the notch C, when the runner is slid up the stick, while the other end of said head has a shoulder, e², against which the lower edge of the sleeve impinges when the runner is slid over the stick, the upper edge of said sleeve then meeting the collar D, and the projections b² b² then extending over said collar. The tendency of the spring e is to fly outwardly at its free end; but it is restrained by a pin, f, having a head, f', passing through an opening, e³, and into the stick A, and this pin also prevents lateral motion of said catch, and keeps the latter aligned with the opening in the notch and groove in the slide.

The operation is substantially as follows: To open the umbrella and cause it to be retained opened, the runner is merely slid up the stick until its ascension is arrested by the collar D. By this time the catch E has passed into the notch-opening c and through the groove b' until its head projects beyond the lower edge of the sleeve b. The catch then springs outwardly, and the shoulder e² prevents the runner from sliding down the stick. To close the umbrella, the spring-catch is depressed toward the stick by thumb-pressure on its head, and the runner then drawn over and away from it. To retain the umbrella closed, any suitable or convenient catch may be employed—for example, one like the upper catch already described, but reversed in position.

It will be noted that the catch described does not require the stick to be cut or sawed in the usual manner, so that the weakening and loss of sticks resulting from such cutting is avoided.

It will further be noted that the manipulation of the runner to effect opening and clos-

ing is exactly the same as that of the common umbrella-runner, so that users thereof do not require to be educated into a new method of opening and closing, but will fall to this device naturally and intuitively.

It will be noted that the groove b' does not open to the outside, and is therefore not a slot. It forms a closed passage-way, open only at the ends and on the inner side.

10 What I claim as my invention is—

1. The umbrella - runner B, composed of sleeve b and notch C, said sleeve having a groove, b' , and said notch having an opening in alignment with and forming an entrance thereto, substantially as shown and described.

15 2. The catch composed of collar D and spring e, having head e' , substantially as shown and described.

3. The combination, with stick A, of collar

D, secured thereto by pins d d , spring e, having head e' , and restraining-pin f, substantially as shown and described.

4. The combination, with umbrella-runner B, comprising grooved sleeve b and notch C, with opening c , of spring-catch E, having head e' , and secured to a collar, D, whereby when said runner is slid up on the umbrella-stick it is caused to pass over the spring, and is caught and retained between the head thereof and said collar, as set forth.

In testimony that I claim the foregoing I have hereunto set my hand this 5th day of June, A. D. 1883.

JOHN B. POWELL.
